SPARK PLUG

Edgar R. Holmes, Denver, Colo., assignor to
 Holmes Induction Devices, Inc., Denver, Colo.,
 a corporation of Colorado

Application November 6, 1939, Serial No. 303,068

7 Claims. (Cl. 123—169)

This invention relates to improvements in ignition devices and has reference more particularly to an ignition device of the type employed in connection with internal combustion engines and popularly referred to as "spark plugs."

It is well understood that the efficiency of a spark plug or ignition device depends upon the character of the spark produced thereby. If a big intense spark is produced, the ignition will be initiated with greater force and the resultant combustion of the gases will take place more quickly and be effected more thoroughly than if the ignition was started by means of a weak spark.

It is the object of this invention to produce a spark plug of a simple and substantial construction that shall embody a new combination of elements and structures by means of which an intense spark will be produced when such a plug is substituted in an ordinary ignition circuit for the spark plugs now in common use.

Another object of this invention is to produce a spark of such construction that the magnetic effect of the electric current is taken advantage of for the purpose of intensifying and prolonging the spark.

A still further object is to produce a spark plug in which a condenser effect is provided that tends to effect an accumulation of electricity which will be suddenly released with the result that the spark will have greater volume than ordinarily.

It is commonly accepted that high tension currents produced by an inductive action are highly oscillatory in character and therefore in accordance with the well known theory commonly referred to as "skin effect" such currents travel primarily along the outer surface of the conductor provided for their guidance.

It is also well understood and accepted that an electric current traveling through a conductor will set up magnetic lines of force that travel around the conductor in a clockwise direction when viewed in the direction in which the current travels. When such a current travels in a helical path, these lines of force combine and form a magnetic field of an intensity corresponding to the number of turns and the value of the current. This principle is taken advantage of in the production of electric magnets, transformers and other inductive apparatus.

An electric current will travel along the path of least resistance and therefore if the conductor through which the current is passing has paths of various resistance, the current will be divided

among such paths in proportions inverse to the value of the resistance.

The spark plug or ignition device which forms the subject of this invention is constructed in such a manner that advantage is taken of the above characteristics of an electric current and in such a way that these characteristics are made to produce a spark of greater intensity than that normally obtained.

In order to explain the invention in such a way that it can be readily understood, reference will now be had to the accompanying drawing in which the invention has been illustrated in a spark plug and in which:

Figure 1 is a side elevation of a spark plug constructed in accordance with this invention;

Figure 2 is a longitudinal, diametrical section through the spark plug shown in Figure 1;

Figure 3 is a bottom plan view looking in the direction of arrow 3, in Figure 2;

Figure 4 is a perspective view of the spark gap electrodes; and

Figure 5 is a fragmentary section showing the distribution of the magnetic lines of force.

In the drawing reference numeral 6 represents a body member of insulating material preferably made from sillimanite. The lower end of this body is provided with a threaded portion 7 of somewhat smaller diameter than the part directly above, which has been designated by reference numeral 8. A shoulder 9 is formed between the sections of different diameter; that portion of the insulating body above the shoulder 9 has been shown as of circular cross section and gracefully curved so as to give a pleasing appearance.

The lower end of the threaded section terminates in the cylindrical tubular member 10. The insulating body 6 has an opening extending longitudinally throughout. The upper portion of this opening is provided with coarse threads 11 and terminates in an inclined shoulder 12 which joins the threaded section with the cylindrical opening 13 that extends downwardly through the part designated by numeral 10. A central electrode 14 which is made of some highly refractory material, such as Nichrome is attached at its upper end to a short metal section 15 whose outer surface is threaded so as to cooperate with the threaded opening 11. A layer of cement 16 surrounds the electrode 14 and positions it firmly in the insulating member. The upper end of electrode 14 has a cylindrical opening in which is positioned a metal plug 17 of nonmagnetic material, such, for example, as copper. The electrode preferably has a pressed fit

with the opening in member 15 so that the two form an assembly that can be readily handled during the manufacture of the plug. A metal base 18, which may be made of steel or of any other suitable material, is provided with a central opening of different diameters. The upper portion of the opening in base 18 is internally threaded so as to cooperate with the thread 7 on the insulating body 6. The threaded opening in the base 18 terminates in a downwardly inclined shoulder 19 that is positioned a short distance below the inclined shoulder 20 of the insulating body and the space formed between the two is filled with a suitable cement 21. The upper 10 end of the opening in base 18 has an enlarged portion 22 that is also filled with a suitable cement 23. After the insulating body has been threaded into the base and the cement hardens, the two parts form a nonseparable assembly 15 which is sealed against leakage. The lower end of the base terminates in a tubular threaded section 24 that is provided with a downwardly flaring opening; a metal electrode 25 is positioned 20 in a groove 26 on the inside of the tubular member 24. This electrode has been shown in perspective in Figure 4 and in plane view in Figure 3 and from these figures it can be seen that it is provided with four inwardly extending arms 27 that terminate a short distance from the outer 25 surface of the electrode 14. This construction provides four spark gaps in parallel. A gasket 28 is positioned beneath the shoulder 29 of the base to form a seal between this shoulder and the engine block. Threadedly connected with 30 the upper end of the opening in the insulating body is a tubular electrode 30. This electrode has a portion 31 of somewhat larger diameter and which forms a shoulder 32 at the place where it connects with the threaded section 30. The 35 upper end of the opening in the insulating member is of increased diameter as indicated at 33 and the space thus formed is filled with a cement 34; above the knurled section 31 there is a neck 35 of somewhat smaller diameter that 40 terminates in a head 36 which is provided with an annular groove 37. The tubular conductor terminates at a point indicated by reference numeral 38. It will be noted that the inner surface of the tubular conductor is provided with threads 45 39 of fine pitch whose function will hereinafter be explained. Positioned in the upper end of the opening in the tubular conductor is a tubular insulating member 40 into which the upper end of a core 41 of magnetic material projects. The 50 lower end of the opening in the tubular conductor 55 has a smooth inner surface and positioned in this is a tubular sleeve 42 whose lower end is provided with a head of somewhat larger diameter which serves as a means for limiting the inward movement of the sleeve. The opening in sleeve 42 is slightly larger than the diameter of the core 41 which therefore can move freely therein. The lower end of the core 41 is tapered so as to form a conical surface in the manner 60 indicated by reference numeral 43 and the point of this rests on the plug 17 which, in the embodiment shown, has a conical depression for the reception of the conical point 43. It will be observed that the tubular conductor terminates 65 a short distance above the part 15 and that the lower end of the sleeve 42 also terminates above this part and therefore there is no direct electrical connection between the two except that which is afforded by the core 41. Since the 70 upper end of core 41 is positioned in the insu-

lating cap 40 and held in axial alignment with the opening in the tubular conductor and since the point 43 is centered by the action of the conical surface on which it rests, this core is not electrically connected with the tubular conductor, but is separated therefrom by a gap 44 which is the distance between the inner wall of the sleeve 42 and the outer surface of the core. It will be observed that the core 41 can move longitudinally to a limited extent, although this is not a necessary requirement. The core is made shorter, principally for the purpose of facilitating assembling because if it were slightly too long, it would be put under considerable compression during the assembly of the plug. 15

Let us now assume that the tubular electrode 30 is connected to the secondary of a high tension transformer which has been designated by reference numeral 45 whose outer terminal is grounded. A high tensioned current will now 20 flow downwardly through the tubular conductor and across the spark gap 44, thence downwardly through the electrode 14 and across the spark gaps provided between it and the electrodes 27. Due to the fact that the tubular electrode is 25 quite thin and to the further fact that the threads on the outside are coarse, the path of least resistance will be along the threads and therefore some of the current will travel helically around this electrode. If the current was direct and 30 of a low tension, there would be a considerable portion traveling in a straight line, but due to the high tension above referred to, a greater proportion of the high tension current will follow the threads with the result that an effect will 35 be produced substantially as if the current were passing through a helix. This helical flow of the current produces a self-induction which resembles that obtained by an ordinary induction coil and this induction, as is well known, first 40 tends to retard the flow of the alternating current and then tends to keep it flowing in the direction in which it is flowing and on reversal an inductive kick is produced which serves to intensify the spark. The fine threads on the 45 inside act somewhat as a secondary winding where high tension alternating current is employed. However, the principal effect is believed to be due to the helical travel of the current in the coarse threads on the outside. The inductive 50 effect is greatly enhanced by the presence of the magnetic core as this can be made from soft iron which has a great permeability and therefore tends to increase the number of lines of the magnetic forces. 55

It has been customary to provide electrodes with an auxiliary spark gap as this has proven to be beneficial in its action as it seems to produce a damming effect of the current with the resultant heavier spark when the electrical tension has increased sufficiently to break down the spark gap. The effect of the auxiliary spark gap is obtained here by spacing the core 41 away from the inside of the sleeve. 60

In Figure 5 a diagram has been shown in 65 which the path of the alternating current has been designated by a dot and dash line 46, the path of the magnetic flux being indicated by lines designated by reference numeral 47. The arrow point 48 shows the place where the current 70 jumps from the tubular conductor to the core 41.

Particular attention is called to the importance of the core of magnetic material as the effect of the magnetizing action of the current is great- 75

ly increased by the presence of a soft iron core. It is possible to substitute for the soft iron a permanent magnet, but due to the permanency of the magnetism, the action is asymmetrical and it is believed that the symmetrical effect produced by a soft iron core is superior, although the permanent magnet has a beneficial effect over that obtained if a nonmagnetic core were used.

10 Comparative tests extending over a considerable length of time have shown that the ignition obtained by means of spark plugs constructed in the manner above described is far superior to that obtained with the ordinary spark plugs and in many cases this effect is so marked as to be readily apparent to any one driving the automobile thus equipped.

It is evident that the threads can be made deeper than shown on the drawing and that the 20 root portions can be closer to the inner surface of the tube so as to make the helical travel of the current more pronounced with the frequencies below those resulting in skin effect. The pitch of the threads and their depth, as illustrated on the drawing, are merely for the purpose of explaining the construction and operation and are not intended to be considered as indicating the exact scale as it is evident that 25 variations in pitch and depth can be made so as to obtain the best results.

Having described the invention what is claimed as new is:

1. A spark plug central electrode formed from two spaced sections, one of which is tubular, a 20 core of magnetic material in the tubular section, the core being of smaller diameter than the opening in the tubular section, an insulator separating the magnetic core from the tubular electrode section, one end of the core being in electrical contact with the other electrode section.

2. An electrode for a high tension spark gap comprising a tubular electrode whose outer surface is provided with a coarse helical thread on its outer surface, a core of conducting material 25 in the electrode, the core being smaller than the opening in the electrode and an insulator separating the core electrically from the electrode.

3. A center electrode for use in a spark plug comprising two electrode sections adapted to be 30 assembled in aligned position in an insulating body, said sections being spaced apart, one of said sections being tubular and provided on its outer surface with a coarse thread, an iron core positioned in the tubular section, the core being 35 of smaller cross section than the opening in the electrode, and an insulator spacing the core from the tubular electrode section, the core having one end in electrical contact with the other electrode section.

4. A spark plug having a tubular body of insulating material, the opening having a helical groove, a central electrode formed from two spaced sections electrically insulated from each other, one of which is tubular, a ridge of electrical conductive material extending helically 40 around the tubular section, said ridge being positioned in the helical groove, a core of magnetic

material in the tubular electrode, the core being of smaller diameter than the electrode, means comprising an insulator for centering the core in the electrode and for spacing it therefrom, the core having one end in electrical contact with the other electrode section.

5. In a spark plug having a tubular base of conducting material provided at one end with a threaded outer surface for effecting a connection with an engine, and a tubular body of insulating material having one end positioned in the base and secured thereto, a portion of the wall of the opening in the tubular insulating member having a coarse helical thread, a central electrode formed from two spaced sections 10 positioned in the insulating member, one of said sections being tubular and provided on its outer surface with a coarse helical thread for engagement with the threads in the insulating body, a core of soft iron positioned in the tubular electrode section, the core being of smaller diameter than the opening in the tubular electrode section, means comprising an insulator for centering the core in the opening, in the tubular electrode section and for insulating it therefrom 15 whereby a spark gap is formed, one end of the core being in electrical contact with the other section of the electrode.

6. A spark plug comprising a tubular metal base having a portion of its outer surface threaded for engagement with a threaded spark plug opening, the inner surface of the opening at the other end being threaded, a tubular body of insulating material adapted to be positioned in the tubular base, the outer surface of said body 20 being threaded for engagement with the threads in the base, the insulating body having a central opening of different diameters, the lower end being smaller than the upper end, the wall of the larger section of the opening being provided 25 with coarse threads, a central electrode formed from two separate parts, positioned in the opening in the insulating body, the lower part extending through the opening of smaller diameter, the upper section of the electrode being tubular 30 and provided on its outer surface with threads for engaging with the threaded wall of the insulating body, the adjacent ends of the electrode sections being spaced apart, a core of magnetic material of high permeability positioned in 35 the tubular electrode section with one end contacting the other electrode sections, the core being smaller than the opening in the tubular electrode section, and means comprising an insulator for centering the core therein and for insulating it therefrom whereby a spark gap is formed.

7. A spark plug central electrode formed from two spaced sections, one of which is tubular, a core of conducting material in the tubular section, the core being of smaller diameter than the opening in the tubular section, an insulator separating the conductive core from the tubular electrode section, one end of the core being in electrical contact with the other electrode section.
